UNITED STATES PATENT OFFICE.

WILHELM SCHWEDE, OF FOLEY, MINNESOTA.

WHEAT HEATER.

Application filed December 17, 1921. Serial No. 523,235.

To all whom it may concern:

Be it known that I, WILHELM SCHWEDE, a citizen of the United States, residing at Foley, in the county of Benton and State of Minnesota, have invented certain new and useful Improvements in Wheat Heaters, of which the following is a specification.

This invention relates to wheat heaters for use in flour mills, and more particularly to heaters of the upright gravity type, an object of the invention being to provide a gravity heater, in combination with grain elevating means, whereby the grain is repeatedly subjected to a falling movement to cause it to fall into momentary contact with a plurality of steam coils, the repetition of the falling movement occurring in regular progression from the point of intake, laterally across the machine to the point of discharge.

A further object of the invention is the provision of novel interior baffles, arranged relative to the coils, to cause each kernel of wheat to fall in a zig-zag course to engage alternately, the baffles and the coils throughout its falling movement, whereby each kernel is brought into contact with the several coils, the device being so constructed as to cause the kernels to revolve in their descent.

A further object of the invention is to provide a heater of the class described wherein the grain will be evenly heated, owing to feeding provisions, whereby the main entering column of grain is separated into a plurality of columns of falling wheat, scattered throughout the heating elements, the wheat constituting the divisional columns, being conducted by laterally pitched ducts at the end of its fall, to elevating mechanism to be thereby elevated to a new portion of the coil, thus causing the grain to repeatedly engage with new portions of the heating elements, from the time of its entry into the machine to the time of its discharge.

A further object of the invention is to provide a heater of the class described, wherein the grain cannot become seriously overheated as is the case with some columnar gravity type heaters, wherein the grain at times rests for seriously long periods against the heated surface, owing to the roughness of the walls of the heating element and the side pressure developed by the column of wheat. This I accomplish by dividing the main column of wheat entering at the intake, into many thin columns, and then dis-

tributing these columns at regular intervals transversely of the coils, to engage different coil members forming the heating units, in its journey from one end of the machine to the discharge opening, so that the kernels of a specific thin column cannot fall continually on the same coil member, and thus subject it repeatedly to any irregularity of temperature in any particular coil member. This is a very important feature as overheated or underheated grain precludes the making of good flour.

A still further object of the invention is to provide ample storage room at the base of the machine underneath the heating elements, so that when a mill is compelled to shut down temporarily, the falling grain will not accumulate in the interim to an extent to cause it to engage with the hot coils, the machine being also designed with a view to aerating the grain in its fall, or, in other words, permitting the grain to fall loosely in its descent so that the kernels will bound singly in a zig-zag course.

A further object of the invention is to provide means whereby each series of coils will receive a constant definite quota of grain, as distinguished from heaters, especially of the rotary type, wherein the grain is dashed in greater volume against one side of the coil than the other, thus effecting uneven heating, and uneven functioning of the coils, the coils in the present invention being also divided into sections so that one or more sections may be operatively detached when desired.

To this end the invention consists in the novel features of construction, combination and arrangement of parts hereinafter described and claimed.

In the drawings forming part of this specification:

Figure 1, is a perspective view of the outside of the machine partly broken away to show the discharge opening within the casing.

Figure 2, is a vertical sectional view on line 2—2 of Figure 1.

Figure 3, is an isometric perspective view showing the interior construction of the machine, one end wall having been removed and the top and sides being broken away.

Figure 4, is a fragmentary perspective view of the distributing devices for distributing the grain over the coils.

Figure 5, is a fragmentary perspective

view, drawn to a reduced scale, of the elevator conveyor, three buckets only being shown.

Figure 6, is a vertical sectional view on line 6—6 of Fig. 1.

Figure 7, is a front view of the upper shaft bearing of the elevator conveyor.

Figure 8, is a side view of the handle end of the shifting rod forming part of the grain shifting mechanism below the heating units.

Figure 9, is a perspective view showing a specific preferred construction of the internal baffles, and

Figure 10, is a vertical sectional view of the shut-off valves for the heating pipes.

Referring to Figure 1, of the drawings, A designates an outer, long, narrow, rectangular, relatively high casing or shell, the walls thereof preferably formed of sheet metal, backed with asbestos sheeting, for the purpose of better retaining the heat. The casing is constructed with a removable side wall 1, forming one of the long sides of the casing, preferably secured in position by bolts having wing nuts 2, whereby access to the interior of the casing may be had.

Generally, the casing consists of end walls 3 and 3', and a secondary long side wall 4, the latter being somewhat less in height than the wall 1, the two side walls being joined by an inwardly inclined removable top wall portion 5, and a permanent curved top wall portion 6, said removable wall 5, being also secured in position by bolts and wing nuts similar to the wall 1. By removing the top wall 5, access to the upper portion of the interior of the casing may be had.

Extending through the wall 3, at a point above the side wall 4, is the intake or feed hopper 7, the floor 8 of the casing having adjacent the end wall 3', the discharge opening 9, through which the grain may pass to the wetting bin, not shown, by means of the conductor pipe 10.

Generally, the invention consists of elevating mechanism B, radiating batteries of coils C, grain distributing devices D, and shiftable gate or duct mechanism E. The interior of the casing A, is constructed with a secondary floor, consisting of a flat plate 11, extending from the wall 4 downwardly and inwardly, to the main floor 8, and beyond the longitudinal center of the latter, and a curved floor portion 12, merging into said plate so as to form a trough the arcuate bottom thereof being concentric with the shaft 13, which latter extends longitudinally of the casing and parallel with the sides and bottom thereof. Vertically aligned with said shaft and parallel therewith, and preferably concentric with the curved top wall 6, of the casing, is the shaft 14. The shaft 13 extends through the end walls 3 and 3', and is journaled in the journal boxes 15

which are suitably secured to the respective end walls.

Set screwed collars 16 on the shaft between the journal boxes and the end walls, serve to retain the shaft in position. The shaft 14, also extends through the respective end walls, and is provided with similar collars 16, and is journaled in the journal boxes 17, said journal boxes being formed with a pair of laterally extending arms formed with flanges 18, having vertically disposed slotted bolt holes 19. Extending upwardly from the journal box, is the arm 20, the latter being formed with an outstanding lug 21 through which loosely extends the vertically disposed adjustment screw 22, having a suitable hand wheel 23, said adjustment screw having threaded engagement with the lug 24, extending outwardly from the top of the casing. The adjustment screw is formed with a head underneath the lug 21, so that when the screw is revolved the journal bearing may be bodily moved, a suitable bolt in each of the slotted holes 19, and extending through the end walls, serving to hold the journal box positioned. Thus, the shaft 14 may be adjusted vertically to be raised or lowered as the case may be.

Rigidly secured on the respective shafts, are the sprockets 25, which latter are positioned in vertical alignment and are operatively connected by the sprocket chains 26, whereby the two shafts may be rotated by means of the belt driven pulley 27, which is shown mounted on the lower shaft 13, but may be carried on either shaft.

A relatively wide belt 28, is suitably secured to the sprocket chains, and travels with the latter, said belt being preferably made of woven fabric such as canvas and the like as shown in Figure 5, of the drawings. A plurality of long buckets 29 angular in cross section are suitably secured to the sprocket chains and belt, and are spaced at regular intervals throughout the length of the latter. The buckets are arranged on the belt in a manner to scoop up and carry grain from the trough below to the top of the casing and discharge it toward the wall 4 thereof said buckets extending between points adjacent the end walls of the casing. The slack in the belt may be regulated by the adjustment screw 22 at the top of the casing.

Extending vertically longitudinally of the casing, thereby dividing the latter into chambers F and G, and located approximately midway between the side walls thereof, and supported as by means of the bolts 30 on the end walls thereof, and spaced an appreciable distance, from the top wall portions and the bottom of the casing is the partition wall 31. The upper portion 31' of the partition wall inclines slightly toward the elevator mechanism, which latter occupies the

chamber F on one side of the partition walls, and extends above and below the latter, as is best shown in Figure 2 of the drawings. The elevator mechanism is thus rendered accessible by the removable side wall 1, and is disposed in the casing relatively to the partition wall, so as to discharge the grain beyond the inclined portion 31' thereof, the belt 29 functioning as a means for directing the grain.

Located in the chamber G, above the secondary floor plate 11, and below the top of the side walls 4 of the casing, are the radiating batteries of heating coils or units C, arranged in tiers.

An object of my invention is to provide a construction for heating units which will be inexpensive, durable and efficient, and will provide a large heating surface and be capable of being housed in a relatively small space, whereby the machine is rendered compact and relatively small in size. This, I accomplish, by providing end supporting plates 32, extending preferably from the floor 8, vertically in parallelism with the end walls of the casing, to a point above the heating units. As is best shown in Figure 2 of the drawings, these supporting plates are perforated by four vertical rows of circular apertures 33, said rows arranged in lateral alignment, and the apertures of all of the rows being uniformly spaced both vertically and laterally, said rows of holes being spaced uniformly as a whole from the side walls of the chamber G. Midway between said rows of apertures, are vertical rows of apertures 34, spaced at intervals similar to the rows of apertures 33, and in alternate relation to the latter. The apertures 34 are preferably of square configuration, one diagonal of the square, being vertically disposed and parallel with the side walls of the chamber G. The edges of the supporting plates 32 are formed with V-shaped notches 35, corresponding to a half portion of the square apertures 34, and being in lateral alignment therewith for purposes hereinafter to be explained.

The round and square apertures are thus arranged symmetrically in interspaced relation one above the other in regular alternating relation both vertically and laterally.

As shown in Figure 3, each heating unit consists of a coil composed of a plurality of coil members or of pipes and has an inlet terminal 36, and an outlet terminal 37, which latter extends through the plate 32 and through and beyond the end walls 3. Each unit, as shown, consists of twelve horizontal pipe or coil members connected to form coils arranged in three flat layers of consecutively connected pipes, one above the other to bring the respective inlets of all the units in vertical alinement on one side of the chamber G, and the respective outlets

in vertical alinement on the opposite side of the chamber G.

The pipes of each unit are connected by suitable return fittings 38, which are located between the supporting plates 32 and the end walls of the casing, and are adapted to abut with their inner faces against said supporting plates whereby to sufficiently overlap the circular apertures to form a suitable enclosure to prevent grain from leaking therethrough.

As best shown in Figure 1, the inlets 36, and the outlets 37, are provided with shut-off valves 39 (Fig. 10), said valves being connected by the feed pipe 40, which is intended to be connected with a suitable source of either steam, hot water or hot air. By means of the valves each heating unit may be individually shut off to render it inoperative. Likewise, the outlets 37, are connected by similar shut-off valves 39, with an outlet 40, whereby the steam, hot water, or hot air may be discharged, each outlet being thus rendered capable of being shut off at will.

Arranged parallel with the partition wall 31, and bisecting the rows of square apertures 34, and extending beyond the upper and lower layers of heating coil, are the division walls 41, suitably secured at 42 to the supporting plates 32. These division walls serve to divide the heating chamber G into four long narrow vertical passage ways or drying compartments, $a-a'-a''-a'''$, open at the top and bottom, and obstructed centrally by a tier of vertically spaced coil members, formed collectively by a part of each of the three heating units. It should be noted, that any one or all of these parts may be rendered ineffective by the closing of the respective shut-off valves 39, so that if desired, only the parts of the two upper units may be used, if desired, thereby affording regulatory means for controlling the volume of heat. Resting with their legs against the division walls 41, and extending through the square aperture 34, one on either side of the wall, are the baffle members 43, the latter consisting of a right angled angle iron of equal legs, two of which, when oppositely disposed, with the plate 41 between them, will frictionally engage the walls of the square apertures to be thus held positioned and form a leak-proof joint, to prevent grain from passing through. The notches 35 are adapted to receive baffle members, so that the latter will project from the walls 4 and 31, to deflect the grain toward the pipe coils.

The baffles are designed, to slightly overhang the coil members, or, in other words, extend slightly between vertically adjacent coil members, whereby, a kernel of wheat, dropped from above into one of the four drying compartments will progressively alternately contact in its fall, with a baffle

- and coil member, as shown in Figure 2, the kernel in its descent generally acquiring a rotary motion. As the grain is methodically dropped into these drying compartments, 5 (to be hereinafter explained) the streams of flow are relatively thin, to permit no extensive accumulation between the coil members and the baffles, thereby avoiding choking of the flues, and effecting even heating.
- 10 The method of dropping the wheat from above involves grain distributing devices D, best shown in Figure 4. These devices comprise a plurality of groups *d* of preferably open top steeply inclined conductors or 15 ducts 44, for conducting the grain from the elevator B, as it falls over the partition wall 31. These groups of conductors are arranged in a row longitudinally of the machine, the component conductors directed transversely therof and inclined toward and terminating at the partition wall 31. The conductors are preferably quite narrow to render the falling grain column or stream, thin and scattered, each group in the heater 20 shown, consisting of four ducts, *e*—*e'*—*e''*—*e'''*, said ducts being constructed to discharge respectively into the drying compartments *a*—*a'*—*a''*—*a'''*. Inspection of Figure 4, will disclose that *e* leads from the 25 wall 31 directly to the compartment *a*, while the rest of the ducts of the group are cut short by a vertical terminal wall 45, and have a port 46 opening into the respective compartments which they are intended 30 to feed. The inclined upper portion 31' of the partition wall 31, constitutes the upper terminal wall of all the ducts, while the oppositely inclined longitudinal wall 47, extending from the top wall 5 of the casing 35 to the top of the ducts, constitutes a baffle plate to direct the grain discharged 40 from the elevator, to the upper open portion of all the ducts of the groups. A novel inexpensive construction of the group of 45 ducts is effected, by striking the terminal walls 45 out of flat plate, as shown in Figure 4, and slipping the division walls between them. As indicated, each duct, leads by 50 means of its port into its respective compartment. Thus, the streams of grain falling on each coil member, are well separated, as indicated at *b*—*b* on the first coil member to the left of the machine (Fig. 4) thereby 55 enabling the kernels to spread in their fall to facilitate even heating. The grain is fed from a source of supply through the hopper 7 directly into the ducts, the position of the hopper being indicated by dotted lines in Figure 2.
- 60 The grain falls upon the inclined plate 11, and slides into the trough 12, into the path of the buckets 29 to be returned to the distributing devices D.
- Arranged in a row longitudinally of the 65 casing A, on the plate 11, are the shiftable

runways *g*, formed by spaced vertical gates 48 swingable laterally on the pivot pins 49, extending at right angles from the plate 11. The gates are parallel and extend downward toward the elevator B, each gate being provided 70 with a pivotal connection 50 whereby it is pivotally connected to the shifting rod 51, which latter slidably extends through the plate 32 and the end wall 3' and is provided with a suitable handle whereby it 75 may be manually operated. The rod is formed with notches 52, adapted to engage the wall 3' whereby the rod may be held at any position to which it may be shifted.

As indicated in dotted lines at *h*, Figure 80 3, the gates may be shifted collectively laterally to stand at several selective angles, or pitch, whereby the grain sliding through the gateways may be deflected so as to be scooped up by a different part of the buckets 85 of the elevator, causing it to be discharged progressively farther from the point of inlet, with every revolution of the elevator. Thus, each kernel journeys in a path, which may be said to describe a helix of a pitch 90 95 equivalent to the pitch to which the gates may be set, the kernel traveling gradually in a cycle over the heating units to the elevator and so on toward the discharge opening 9 in the floor of the casing. The wall 95 95 directs the grain to the runways *g*.

I claim:

1. In combination with a grain heater consisting in part of elongated, horizontally disposed heating pipes arranged spacedly 100 side by side to form vertical rows and means whereby the grain is repeatedly precipitated distributively over said pipes; of a device forming part of said means, and consisting of a plurality of groups of chutes disposed 105 transversely of said pipes above the latter, and arranged in a row lengthwise of the pipes, each chute of each group terminating over a different heating pipe.

2. In a grain heater of the class described, 110 the combination with a grain heater consisting in part of tiers of horizontally disposed heating pipes arranged spacedly side by side, the pipes of the tiers being spaced vertically, and means whereby the grain is repeatedly precipitated distributively over 115 said tiers; of vertical walls disposed midway between said tiers of heating pipes and baffles extending downwardly and outwardly from said vertical walls toward said tiers of heating pipes, and between the component pipes of the latter, for the purpose set forth.

3. In combination with a grain heater consisting in part of elongated horizontal heating coils, and means whereby the grain is repeatedly precipitated over said heating coils; of means under the heating coils for diverting the direction of flow of the grain 125 after it leaves said coils, said means consist- 130

ing of a plurality of downwardly inclined open ended contiguous ducts extending generally in a direction transversely of the coils, the walls of the ducts being movably mounted whereby to change the direction in which they extend, and means extending to the outside of the grain heater and pivotally connected to the walls of said ducts for manually moving said walls to change the direction of flow of the grain for the purpose set forth.

4. In a grain heater of the class described, the combination, a casing formed with a discharge opening and an internal heating chamber, horizontally disposed elongated heating coils in said heating chamber, grain distributing devices including ports for distributing grain onto said coils located directly above the latter, power driven lifting and discharging means for lifting the grain from a point below said heating coils and discharging same onto said distributing devices, and means under said coils for conducting the grain into engagement with said lifting means to be lifted thereby, said means including means for diverting the direction of flow of said grain toward said discharge opening.

5. In a grain heater of the class described, the combination, a casing having a discharge opening, and an internal heating chamber, means for distributively precipitating grain from above into said chamber, conducting means including runways for conducting the precipitated grain diagonally laterally toward said discharge opening and away from said heating chamber, a trough at the base of said conducting means to receive the grain, elevating and discharging means adapted to engage with the grain in said trough to elevate the grain and discharging the latter onto said precipitating means to be precipitated thereby, and grain heating means in said heating chamber in the path of the falling grain to engage the latter, said grain heating means consisting in part of spaced parallel vertical rows of elongated horizontally disposed heat radiating cylindrical tubes, and vertical rows of square tubes interposed between said rows of cylindrical tubes, said square tubes alternating vertically with said cylindrical tubes.

6. A grain heater, comprising a casing having a discharge opening and an internal heating chamber, heating units in said heating chamber, said units constructed to form collectively a plurality of vertical rows of horizontally disposed heat radiating tubes, grain distributing devices having a plurality of ports, said devices disposed directly above said rows of tubes, and having their ports in vertical alinement respectively with said tubes, lifting means adapted to be connected with a source of power to be actuated thereby for lifting the grain from a

point below said heating units onto said distributing devices to be thereby precipitated through the ports of the latter, and deflecting means below said heating units adapted to receive the precipitated grain and deflect the latter, in its falling movement somewhat diagonally relative to said heating tubes, toward said discharge openings and said lifting means and into engagement with the latter.

7. A grain heater comprising a casing having a discharge opening and an internal heating chamber, heating units in said chamber disposed one above the other said units constructed to form collectively a plurality of vertical rows of horizontally disposed heat radiating tubes, grain distributing devices above said heating units for distributively precipitating the grain over said tubes, lifting means adapted to be connected with a source of power to be actuated thereby for lifting the grain from a point below said heating units to said distributing devices to be precipitated thereby, means adapted to intercept the precipitated grain in its fall from said tubes and deflect the same toward said discharge opening and into engagement with said lifting means, and means for selectively rendering operative any one of said heating units singly or two or more collectively.

8. In a grain heater of the class described, the combination, a casing having a discharge opening, and an internal heating chamber, horizontally disposed elongated heating coils in said heating chamber, downwardly inclined runways arranged in the path of the grain falling from above through said chamber, beneath said heating coils for conducting the falling grain, said runways directed diagonally relative to said elongated heating coils, toward said discharge opening, power driven grain elevating mechanism, extending from said runways to a position above said heating coils and adjacent thereto and adapted to engage the grain from said runways to elevate the latter and discharge same above and toward said heating coils, and a plurality of groups of ducts above said heating coils adapted to receive the grain from said elevating mechanism, said groups of ducts disposed transversely of said coils, and arranged contiguously longitudinally of the latter, each duct of each group having a discharge opening, and each of said discharge openings arranged to precipitate the grain on a different heating coil.

9. In a grain heater of the class described, the combination with a grain heater consisting in part, of tiers of horizontally disposed heating pipes arranged spacedly side by side, the pipes of the tiers being spaced vertically, walls uniformly separating said tiers of pipes, and baffles extending from said walls outwardly and downwardly to a

point between the component pipes of said tiers; of a supporting structure for supporting said heating pipes and baffles, consisting of a plurality of vertically disposed supporting plates disposed transversely of the pipes at the ends of said walls, and having spaced vertical rows of perforations through which latter said heating pipes are adapted to extend to be supported thereby a vertical 5 row of openings of square configuration between adjacent rows of said perforations and staggered relative thereto, said openings disposed with their sides inclined from the vertical, and a right angled angleiron of equal 10 legs slidably fitting said openings on either side of said separating walls, whereby to form outwardly and downwardly inclined baffles for the purpose set forth.

10. A grain heater comprising a casing 20 having grain inlet and discharge openings at the respective ends thereof, horizontally disposed spaced tiers of heating pipes extending side by side longitudinally of the casing at a lower level than said grain inlet, and means, including elevating mechanism, for distributively dropping the grain fed through said inlet on to said heating pipes and causing the grain to travel in a course describing a helical path from a point below 25 to a point above said heating pipes and to said grain outlet to be discharged therethrough, said means including ducts located between said grain inlet and said heating pipes for initially conducting the grain directly to the individual tiers of said heating 30 pipes.

11. A grain heater comprising in part, a casing, horizontally disposed spaced tiers of heating pipes within the casing extending side by side longitudinally thereof, and 40 means including elevating mechanism for lifting the grain above and discharging it toward said heating pipes, said means including a plurality of grain conducting ducts open at the top each duct having a discharge 45 end, said ducts being so mounted as to receive from above the grain discharged from said elevating mechanism, said ducts being of different lengths to bring their discharge ends into operative relation respectively with 50 different tiers of heating pipes.

12. The combination with a grain heater comprising a casing, spaced tiers of heating pipes arranged side by side in the casing, and means including power driven elevating 55 mechanism for lifting the grain above and discharging it toward said heating pipes; of a grain distributing element in the path of the discharging grain, said element comprising a plate located above said heating pipes 60 and inclined toward said elevating mechanism in the path of the discharging grain, rows of spaced ports in said plate, said rows being respectively in vertical alinement with said tiers of heating pipes, the ports of adjacent rows being arranged in staggered relation, and a vertical wall extending transversely of said rows of ports between the staggered ports thereof for the purpose set 65 forth.

In testimony whereof I affix my signature.
WILHELM SCHWEDE.
